UNITED STATES PATENT OFFICE.

OTTO G. SCHMITT, OF CHICAGO, ILLINOIS, ASSIGNOR, BY DIRECT AND MESNE ASSIGNMENTS, TO BARNHART BROS. & SPINDLER, OF JERSEY CITY, NEW JERSEY, A CORPORATION OF NEW JERSEY.

TYPE-CASTING MACHINE.

1,160,772.

Specification of Letters Patent. Patented Nov. 16, 1915.

Application filed December 13, 1912. Serial No. 736,463.

To all whom it may concern:

Be it known that I, Otto G. Schmitt, a subject of the German Empire, residing at Chicago, in the county of Cook and State of Illinois, have invented a certain new and useful Improvement in Type-Casting Machines, of which the following is a full, clear, concise, and exact description, reference being had to the accompanying drawings, forming a part of this specification.

My invention relates to a multiplex type casting machine and has as its principal object to increase the output and decrease the unit cost of existing type casting machines.

15 A second object of my invention is to cast two type in each revolution or cycle of operation of the machine.

A third object is to increase the percentage of each revolution or cycle during 20 which the type may remain in the mold.

A fourth object is to provide an improved means of operating the ram from a cam so as to increase its speed of movement.

A fifth object is to provide means for 25 varying the width or point of type cast by the machine.

A sixth object is to provide means whereby the type metal is prevented from freezing in passages connected with the mold, and 30 from dripping into the mold.

A further object resides in the particular arrangement and combination of parts hereinafter described.

With these and other objects in view, 35 my invention comprises a plurality of type molds, a matrix which may be used with first one mold and then the other, and means for forcing molten metal into first one and then the other of the type molds.

40 Referring to the accompanying drawings, which form a part of this specification, Figure 1 is a front elevation of my machine, parts of the frame being shown in section and other parts of the frame being broken away; Fig. 2 is a top plan view of Fig. 1; Fig. 3 is a cross sectional view taken on the line 3—3 of Fig. 2, looking in the direction of the arrow, part of the lower central portion being broken away to show one of the 45 mold slots with the connecting nipple and

the pusher finger closing the bottom of the slot; Fig. 4 is an elevational view of the central part of Fig. 1, partly in section, and certain parts being removed; Fig. 5 is a cross sectional view taken on the line 5—5 of Fig. 1, looking in the direction of the arrows, certain parts being broken away; Fig. 6 is a detail view showing the ram and mold block in cross section and the matrix box in side elevation; Fig. 7 is a detail view showing the front elevation of the matrix box; Fig. 8 is a detail cross sectional view through the matrix box immediately above the matrix; Figs. 9 and 9^a give the diagrams of the movements of the principal 65 parts of my machine; and Fig. 9^b gives the corresponding diagrams for previous type casting machines; Figs. 10, 11 and 12 are detail views showing certain cams for operating my machine.

Throughout said views the same part is referred to by the same reference characters.

Referring more particularly to the drawings, 1 is a casting in the form of a horizontal plate, upon which my machine is supported. Suitable brackets not shown are provided for supporting the plate 1 from the floor.

2 is a frame supported on the plate 1 in which the greater portion of the moving 80 parts of my machine are carried. As shown in Fig. 3 the frame 2 is set at an angle to the vertical for a reason to be mentioned later.

3 is a main driving shaft mounted beneath the plate 1, on which are mounted the cams 4, 5 and 6. Shaft 3 also carries a gear 7 which drives the shaft 8 through the gear 9. The shaft 8 is nearly vertical, as appears in Fig. 1 and carries at its upper end a cam 90 10. The cam 10 drives a reciprocating ram 11 by means of a removable pin 12 which has a sliding connection with the ram passing through a hole near the left end thereof, as viewed in Fig. 1. The ram 11 is reciprocated in the guides in the frame 2 as clearly shown in Fig. 5. The combined action of the cam 10 and the pin 12 is such that the ram reciprocates first to the right and then to the left, and pauses or dwells at each end 100

2

of its stroke. By mechanism to be described more in detail later, a type is cast during each pause or dwell of the ram at the ends of its stroke, thus casting two type for each complete reciprocation of the ram or cycle of the machine. The pin 12 is connected at its upper end to a lever 13 which is pivoted in the frame 2 at the point 14. At its left end the lever 13 is forked, as shown at 15—15 in Fig. 2, and each fork is provided with a slot 16 appearing in Fig. 1. A pin 17 passes through the upper end of the pin 12 and slides in the slots 16 in the two forks 15. The lever 13 has a pin connection with the upper end of the vertical slide or chocker rod 18, which is operated by means of the chocker cam 6 shown in Fig. 1. Assuming the ram to be at the right end of a stroke, (Fig. 5) when the rod 18 moves downwardly the pin 12 is forced into the circular portion 19 of the groove shown in the upper face of the cam 10. The pin and ram are then moved to the left, while the pin 12 occupies the portion 20 of the groove 20. As soon as the pin reaches the small circular portion 21, the rod 18 lifts upwardly and withdraws the pin 12 from the groove. The ram has thus been removed from its right hand position to its left hand position, and the pin 12 has been moved from the right hand end of the slot 16 to the left hand end. When now the rod 18 descends upon its next succeeding stroke, the pin 12 will be inserted in the cam groove in the circular portion 21, and the pin 12 will be moved to the right by the portion 22 and the pin will be withdrawn when it strikes the circular portion 19, leaving the ram again in its right hand position.

Now the cam 10 is geared so as to revolve thirteen times as fast as the main shaft 3, while the movement of the ram from right to left occurs in ninety degrees of the cam 10. If we assume that sixteen degrees of arc is the least which can be used to give satisfactory operation of any cam of practical size, it will be seen that the ram is operated at least two times as fast as it could be if it were operated direct from a cam on the shaft 3. But since the time that the type must remain in the mold is fixed, the quicker the movement of the ram and the greater proportion of the cycle which can be used for casting, the faster the main shaft can be driven. I assume that by using the improved ram movement just described I am able to operate the main shaft at twice the R. P. M. heretofore employed. The lever 13 at the end opposite the pin 12 is provided with a sliding pin connection with a second vertical pin 23, as shown in Figs. 2 and 3. The pin 23 is tapered at its lower end so as to engage correspondingly shaped holes in the block 24 fixed to the top of the ram 11. One of these holes appears at 25

in Fig. 2, while the other is immediately under the pin 23 in Fig. 2. The lever 13 is timed so that the pin 23 is forced into one of the holes 25 whenever the ram dwells at the ends of its stroke. The ram is thus held firmly and made to register properly with the mold and other apparatus during the casting process. Immediately below the central part of the ram and carried by portions of the frame 2 is a mold block 26, as best shown in Figs. 3, 4, and 6. The upper portion of the block 26 is of the same width as the central portion of the ram, while the lower portion of the mold block is of greater width than the ram, as clearly appears in Fig. 3.

It will be understood that in practice mold blocks are made in several parts, and are water cooled, but this being well known, will not be described.

To the right of its center block 26 is provided with a slot or groove 27, and at the left of its center with a second slot or groove 28. The type are cast alternately in slots 27 and 28. The bottoms of these grooves are closed by movable fingers 29—29 which are carried at the upper ends of body plungers 30—30. The body plungers 30—30 are operated from grooves in the opposite faces of the cam 5 by means of levers 31. There is a loose connection between the plungers 30 and the levers 31, so that the cam and the levers serve only to lift the plungers and fingers while their downward movement is caused by springs 32—32. The plungers 30—30 are operated only when it is desired to force a type out of the slots 27 and 28, the throw of the slots in the cam 5 being such as to lift the upper ends of the fingers 29 level with the top of the block 26. The slots 27 and 28 are separated by a distance equal to the travel of the ram while their bottoms are closed by the fingers 29. The ram 11 is also provided with two slots or grooves occupied by plates or fingers 33 and 34. The grooves occupied by the plates 33 and 34 are twice as far apart as the grooves 27 and 28. The upper ends of the plates 33 and 34 are embraced by circular pins 35 and 36 which are slidably mounted in sockets descending from the top face of the ram. The upper ends of the pins 35 and 36 contact with adjustable screws 37 and 38 which are carried at the ends of a rock arm 39, which is pivoted at 40 to the face of the block 24. At each side of the mold or block 26 is a type-way 41. The type-ways 41 are spaced apart a distance equal to three times the travel of the ram. A matrix 42 is suspended below a block 43 which moves from right to left with the ram. If the casting face of the matrix is supposed to be pressed against the face of the mold block 26 in register with the slot 27, the machine is ready to cast a type in this slot. Assume

85

95

100

110

115

120

125

130

that two type have been cast previously, one in each of the molds 27 and 28. The molten type metal will now be forced into the slot 27 by mechanism yet to be described. Any type which may have been cast previously in the slot 28 will be cooled. As shown in Fig. 4 the plate 34 will be in register with the slot 28 when the machine is casting a type in slot 27, and the ram will be at the right hand end of its stroke. Immediately before the ram moves to the left the left body plunger is operated so that the left finger 29 pushes the now cooled type from the slot 28 into the lower part of the groove occupied by the plate 34. Such a type is shown at 44 in Fig. 4. The plate 34 will thus be pushed up and by means of the finger 36 and rock arm 39 and connected devices, will push down the plate 33 forcing any type which may be in the groove occupied by plate 33 into the right hand type-way 41. The ram now moves to the left, bringing plate 34 and type 44 in register with the left type-way 41, and plate 33 in register with the slot 27. Meanwhile the finger 29 has been withdrawn the thickness of the type. Metal is now forced into the slot 28 and after a slight pause the right hand finger 29 is elevated, pushing the type from the slot 27 up into the ram groove beneath the plate 33 and forcing the type 44 into the left hand type-way 41. The ram now moves to the right again into the position shown in Fig. 4, whereupon this cycle of operation is repeated. When a type is being cast the top of the mold slot is covered by the central part of the ram.

As previously mentioned, the slots 27 and 28 in which the type are cast are closed at the bottom by means of fingers 29—29 which are carried at the upper ends of the plungers 30—30. It will be evident from inspection of Fig. 4 that the thickness of the type will depend upon the length of stroke of the fingers 29. Since these fingers are operated on the down stroke by means of springs such as 32, the length of their stroke may be adjusted so as to cast type of different thickness. To accomplish this I provide a threaded bolt 45 which is carried in sockets in the fixed blocks 46 and 47, which form part of the frame 2. Mounted on the bolt 45 is a large threaded square nut 48 which carries steps on its upper face. The plungers 30—30 have offset lugs 49—49, each of which carries a stop adapted to contact with one of the stops on the nut 48. By adjusting the vertical position of the nut 48 on the bolt 45 the operator can determine the distance which the fingers 29 can descend on the down stroke and consequently can determine the thickness of the type. For operating the bolt 45 I provide a worm wheel 50 fixed to the lower portion of the bolt, and a worm 51 meshing with the wheel 50. The

worm 51 is carried by a plate 52, appearing in Fig. 1, and has at its outer end a hand wheel 53. The plate 52 carries a counting attachment which may be of any known type, and which is operated from the worm shaft 51. By cutting the threads on the bolt 45 and the worm 51 on the point system, the counting attachment can be made to read the point of the type cast directly on the face of the plate 52, as shown at 54. 75

As previously mentioned the matrix 42 is suspended from the block 43. As best shown in Figs. 5 and 7, the block 43 is mounted between the plates 56—56, which are fastened to the front face of the ram 11. One of the plates 56 carries a guide block 57 which has a pointed edge so as to engage a groove in the side of the block 43, as shown in Fig. 7, the other side of the block 43 being guided by the other plate 56, as shown in Fig. 5, 85 and also by dotted lines in Fig. 7. In this way the block 43 is adapted to slide transversely of the ram 11, and at the same time be transported by the ram. The blocks 57 are held in place by suitable bolts 58. The matrix is held between two horizontal plates 59 and 60 appearing in Figs. 3, 6 and 7. The plate 59 is carried by a sleeve 61 which runs up through the block 43 and is held up against the adjusting screw 62 by means of the spring 63. The plate 60 is attached to a rod or bolt 64 which runs up through the sleeve 61, and is pressed upwardly by means of the spring 65. On the side toward the ram 11 the matrix 42 is held in alignment 100 by two fingers 66—66 which depend from the inner face of the block 43 and are firmly fixed to the block. The matrix is pressed against the fingers 66 by means of a spring pressed finger 67 which is carried by a boss 105 68 at the inner end of the threaded bolt 69. The bolt 69 is carried within a hollow sleeve 70, a spring 71 being provided within the sleeve to force the bolt and finger in the direction of the matrix. The manner in which the finger engages the matrix is best shown in Fig. 8, the lower block 60 being cut away to permit the finger to reach the matrix. A hand wheel 72 is provided by which the bolt can be operated to withdraw the finger 67 110 from engagement with the matrix. The sleeve 70 and parts supported thereby are carried by a plate 73 which is attached to the front of the block 43 at one end. The plate 73 carries an adjustable screw or bolt 74 115 which is adapted to contact with the outer face of one of the plates 56 to limit the movement of the block 43 and the matrix toward the ram 11, and the mold block 26. The screw 74 thus provides means whereby 120 the height of the printing face of the type may be adjusted. As appears in Figs. 5 and 7, the finger 67 lies in such a position that it will tend to force the matrix 42 toward the right, as shown in Fig. 7. The 125

longitudinal position of the matrix is, however, determined by a block 75 which is supported by an arm 76 which depends from the lower face of the block 43. The position of the block 75 can be adjusted by the screw 77 which is carried by the vertical part of the arm 76. The movement of the block 43 in the guides 57, and consequently the movement of the matrix toward and away from the molds is effected by means of a lever arm 78 which appears in Figs. 1, 3 and 5. This arm 78 depends from a hub 79 which is splined on a shaft 80 carried by lugs 81—81 on the front face of the frame 2. The hub 79 thus is enabled to slide longitudinally of the shaft 80. The shaft 80 is rocked in the lugs 81 by means of a lever 82 appearing in Figs. 1 and 2, which extends horizontally from its connection with the shaft 80 to engage the vertical plunger or choker rod 18 previously mentioned. It will be apparent from the relation shown in the drawing, that when the rod 18 rises to withdraw the pin 12 from the cam groove in the cam 10, and to fix the position of the ram by forcing down the pin 23, that at the same time the block 43 by the connections just described, will be forced toward the face of the ram. The matrix 42 will thus be brought over one of the slots in the mold. When, however, the rod 18 descends so as to throw the pin 12 into the cam groove in order to move the ram the block 43 will be moved from the face of the ram, and the matrix removed from contact with the mold, so that it may be transferred to the other mold slot without interference. Since fingers 66 project inwardly or rearwardly from the inside or back face of the matrix the front face of the ram is provided with two grooves such as 83 to receive the fingers. The fingers are shown in the position occupying these grooves in Fig. 5, and are shown moved away from the grooves in Fig. 6. The ram is provided with only two large grooves since the fingers travel with the ram and do not change their position longitudinally thereof, but the mold block 26 is provided with two pairs of smaller grooves such as 84—84, and 85—85, appearing in Fig. 4, to receive the ends of the fingers.

As previously mentioned type metal is forced into the slots 27 and 28 at proper intervals to form the type. The pumping operation is controlled from the cam 4 on the shaft 3. Cam 4 operates a lever 86, best shown in Fig. 11. Lever 86 drives in turn the rod 87 which connects at its upper end with a lever 88 which is pivoted at 89. As shown in Fig. 11 the operation of the cam 4 is such as to lift the rod 87 only, while the down stroke of the lever 88 and the rod 87 is controlled by a spring 90. As shown in Fig. 3 the lever 88 passes through a yoke 91 which is connected to a pump plunger 92.

The plunger 92 reciprocates in a cylinder 93 which projects from the bottom of a metal pot 94. The cylinder 93 is provided with a chamber 95 beneath the plunger 92, and is also provided with passages 96, through which the molten metal may flow from the pot 94 into the chamber 95 when the plunger 92 is raised. As shown in Fig. 11, the cam 4 is designed to lift the lever 88 twice during each revolution so as to give two pump strokes per revolution of the shaft 3. The interior of the pot 94 is provided with a web 97, through which a passage is provided leading from the chamber 95 to a valve chamber 98. Consequently whenever the plunger 92 is depressed by the action of the spring 90 the metal is forced into the chamber 98. Two nipple outlets 99 and 100 lead from the chamber 98 to mold slots 27 and 28 respectively. The connection of chamber 98 and the outlets to the mold slots are controlled by two similar valves such as 101. The valves 101 are carried on stems 102 which connect with vertical blocks 103—103. The upper end of each block 103 connects with a second stem 104 which is parallel with stem 102, both sets of stems 102 and 104 being guided in the sides of the pot 94. On the end toward the ram 11 the stems 104 are provided with enlarged heads 105 which reciprocate in sockets in the wall of the pot 94 and are normally pressed toward the ram by springs such as 106. By the connection between the stems 104 and 102 the spring 106 thus serves to hold the valves 101 normally closed. However, when the block 43 is pressed against the face of the ram on the opposite side thereof from the heads 105, a bolt 107 carried in the ram 11 is pressed by the block 43 against one of the heads 105 so as to open the valve 101 which controls the nipple outlet leading to the particular slot which is then covered by the matrix 42. When the matrix block moves away from the face of the ram the spring immediately closes the outlet. When the ram and matrix block move into the position to cast a type in the other mold slot, the bolt is thereby carried into position to operate the other valve 101. It will be understood the type are only of the length equal to the width of the plates 33. This length is indicated in Figs. 3 and 5. The rear portion of the mold slots is accordingly made tapered as indicated also in Fig. 5. The rear portion of the fingers 29 is consequently made of somewhat wedge shaped cross section which produces an edge 108, as shown in Fig. 3. It will be understood that the mold block being water cooled the type metal will solidify along the whole length of the mold slot, and consequently that a wedge shaped spur or jet will be cast on the rear end of the type. When the type are pushed up out of the mold slots by the fingers 29 these spurs 100 105 110 115 120 125 130

are received in recesses 109 in the rear edge 5 of the ram 11 appearing in Figs. 5 and 6. Suitable knives (not shown) are fixed to the frame of the machine to break off these spurs and trim the rear end of the type 10 while the type are being transferred by the ram from one of the mold slots to the type-way 41. Other knives such as 110—110 and 111—111 are provided for trimming the 15 other faces of the type, while it is being moved after having been cast.

The metal pot 94 previously mentioned is carried on a casting 112 which is mounted above the base plate 1, and carries a suitable 15 burner 113 for keeping the type metal in a molten condition. Fastened to the upper 20 edge of the metal pot 94 is also a bridge shaped casting 113^a in the horizontal portion of which is slidably mounted a rod 114 which connects with the top of the yoke 91. The upper end of the rod 114 carries nuts 25 against which a spring 115 is adapted to act in order to take up lost motion between the lever 88 and the yoke 91. It has been previously mentioned that the frame 2 is set 30 at an angle to the vertical. This causes the mold slots such as 27 and 28 to incline to the rear and enables the nipples 99 and 100 also to be placed on an inclination so that 35 the metal will drain back out of the nipples into the chamber 98 as soon as the plunger 92 lifts and before the valve 101 is closed.

This prevents all danger of the metal 35 freezing in the nipples, and also avoids danger of the metal dripping into the mold.

Referring to Figs. 9 and 9^a, which indicate diagrammatically the movements of my machine and comparing these movements with those shown diagrammatically in Fig. 40 9^b, it will be seen that the matrix remains in contact with the mold during each casting 45 operation for a greater part of each revolution, or cycle, than is the case in the old machine, although two type are cast from one matrix per revolution instead of one. Also it will be seen that each type remains 50 in its mold for a much greater part of the revolution. This enables me to increase the speed of operation of the machine as previously explained, since the minimum length 55 of time which the type can stay in the mold is fixed by the time required to set. Comparing now the straight line diagrams representing the cam movements in my machine with the old machines we see that the 60 chocker cam performs the functions of both the chocker and matrix cam, thus eliminating one cam, that the pump cam operates twice in each revolution instead of once, 65 that the dressing cam is omitted, that the body plunger cam operates twice in each revolution instead of once, and that the period of movement of the ram is very much shortened.

65 It will be understood by those skilled in

the art that various changes and modifications may be made in the device shown and described herein without departing from the spirit of my invention, and that I contemplate all such modifications and rearrangements as are mechanically the equivalent of the device shown and described herein.

Having thus described my invention, what I claim is:

1. A type casting machine comprising two 75 stationary molds, a ram movable between said molds, and a matrix box mounted upon the ram and positioned so as to come into position to coöperate with each of said molds in turn.

2. A type casting machine having two 80 molds and a matrix box, in combination with means for bringing said matrix box into register with one and then with the other of said molds.

3. A type casting machine having a plurality of molds, a ram carrying a matrix box and a device for registering said ram and matrix box in the same position in front of one or another of said molds.

4. A type casting machine having a ram and matrix box, and a registering pin device for accurately adjusting the ram and matrix box in its extreme right and left positions.

5. A type casting machine comprising two 95 molds and two type race-ways, a ram having two type outlets and means for alternately registering the ram with the two molds and two type race-ways corresponding to the extreme right and left hand positions of the 100 ram.

6. A type casting machine comprising a ram carrying a matrix, two molds and a stop motion for rapidly advancing the ram to right or left position and permitting the 105 ram, after it has traveled to the right or left, to remain idle for a given period with the matrix in register with one or the other of said molds.

7. A type casting machine having a ram, a 110 high speed cam, and a special engaging and disengaging pin for connecting and disconnecting the ram with the high speed cam which imparts right and left motions to the ram and at the same time, permits the ram 115 to remain idle for a given period at the end of each left or right hand movement.

8. A type casting machine having a matrix, two molds, a metal pot, a pump, nipples leading from the pump to the molds, means 120 for associating the matrix with one and then the other of said molds, and means for supplying said molds with metal when they are associated with said matrix.

9. A type casting machine comprising in 125 combination, two molds, two nipples connected to said molds, valves for said nipples and means for automatically and alternately opening said valves.

10. A type casting machine having a mov- 130

able matrix box, two molds coöperating therewith, a metal pot carrying two nipples, and valves for said nipples controlled through the forward and backward motion of the matrix box to supply said molds.

5 11. A type casting machine comprising in combination, a metal pot, two nipples for said pot, a pump, means for actuating said pump twice in each cycle of the machine, 10 and means to alternately direct the metal through one or the other nipple.

12. The combination of a plurality of type molds, a matrix which may be used with first one mold and then another, and means for 15 forcing molten metal into the mold which is for the time being associated with the matrix.

13. A type casting machine having a ram provided with a plurality of type receiving 20 grooves, means for giving said ram a periodically reversing movement, a plurality of molds, means for casting type in said molds, a single matrix box carried by said ram and coöperating with said molds, and means for 25 transferring type from said molds to said grooves.

14. A type casting machine having a matrix and a plurality of molds, and means whereby said molds may be used one after 30 another with said matrix to permit the casting of a plurality of type in said plurality of molds with but a single matrix.

15. A type casting machine having a matrix and a reciprocable ram in combination 35 with means whereby two type are cast from said matrix during each complete reciprocation of said ram.

16. A type casting machine comprising in combination a plurality of molds, a matrix, 40 and means whereby all of said molds are used in connection with said matrix.

17. A type casting machine comprising in combination, a plurality of fixed molds, a single matrix, and means for transporting 45 said matrix from one mold to the other.

18. A type casting machine comprising in combination, a plurality of fixed molds, a single matrix, means for transporting said matrix from one mold to the other, and 50 means for adjusting said matrix against the face of the molds.

19. A type casting machine comprising in combination, a reciprocable ram, a cam for driving said ram, an element for operatively 55 connecting said ram with said cam, and means for disconnecting said element from said cam.

20. A type casting machine comprising in combination, a reciprocable ram, a cam for 60 driving said ram, a pin having sliding connection with said ram, and means for moving said pin into operative connection with said cam at intervals.

21. A type casting machine comprising in 65 combination, a ram, a pin having sliding

connection with said ram, a rotating cam having a groove therein, a portion of which is concentric with the axis of rotation of the cam, and a portion of which is eccentric to said axis, and means for inserting said pin 70 into the concentric portion of said cam groove.

22. A type casting machine comprising, in combination, a reciprocable ram and a matrix box mounted on said ram.

75 23. A type casting machine comprising in combination, a reciprocable ram, and a matrix box mounted to reciprocate with said ram and having a movement transverse to the movement of the ram.

80 24. A type casting machine comprising in combination, a reciprocable ram, a matrix box mounted on said ram and means for moving said box relatively to said ram.

85 25. A type casting machine comprising in combination, a reciprocable ram, guides fastened to and extending out from one face of said ram, a slideable block carried by said guides, a matrix held by said block, and means for moving said block back and forth 90 in said guides.

95 26. A type casting machine comprising in combination, a pair of molds and a ram carrying a single matrix coöperating with both of said molds.

100 27. A type casting machine comprising in combination, a reciprocable ram provided with a pair of slots, slideable fingers mounted in said slots, and a pivoted arm for transmitting motion from one finger to the other.

105 28. A type casting machine comprising a reciprocating ram carrying a matrix, two molds, and means for positively holding said ram at the ends of its stroke in register with one or another of said molds.

110 29. In a type casting machine, a matrix box comprising a movable block, means for guiding said block, a matrix and yielding means for supporting said matrix from said block in combination with a ram carrying 110 said matrix box.

115 30. In a type casting machine in combination, a reciprocating ram, guide means attached to said ram, a movable block carried by said means, a matrix, a pair of plates between which said matrix is mounted, and means for supporting said plates from said block.

120 31. In a type casting machine in combination, a reciprocable ram, guide means attached to said ram, a movable block carried by said means, a matrix, and a pair of plates clamping said matrix provided with spring connection with said block.

125 32. In a type casting machine in combination, a reciprocable ram, guide means attached to the face of said ram, a movable block carried by said means provided with an aperture, a plate provided with a sleeve passing through said aperture, a spring act. 130

ing against said sleeve for holding said plate in position, a second plate having a rod extending through said sleeve, a matrix mounted between said plates and a spring for forcing said second plate against said matrix.

33. In a type casting machine in combination, a reciprocable ram, guide means attached to said ram, a movable block carried by said means, a matrix supported from said block, and means for adjusting said matrix relatively to said block.

34. In a type casting machine in combination, a reciprocable ram, guide means attached to said ram, a block carried by said means, a pair of spring held plates mounted on said block, a matrix mounted between said plates, and means for adjusting the position of said plates with reference to said block.

35. In a type casting machine in combination, a reciprocable ram, guide means attached to said ram, a block carried by said means provided with fingers, a pair of spring held plates carried by said block in proximity to said fingers, a matrix held between said plates, and means for forcing said matrix against said fingers.

36. In a type casting machine in combination, a reciprocable ram, guide means carried by said ram, a block carried by said means provided with depending fingers, plates mounted below said block in proximity to said fingers, springs for supporting said plates from said block, a matrix carried between said plates, and a spring pressed finger for forcing said matrix against said fingers.

37. In a type casting machine, a matrix box comprising in combination, a block provided with a depending right angled arm or lug, a pair of horizontal plates mounted beneath said block, springs for holding said plates in position, a matrix held between said plates, means for adjusting the vertical position of said plates, a vertical plate carried by said lug, contacting with one end of said matrix, and a screw for adjusting the position of said vertical plate.

38. In a type casting machine, a matrix box comprising in combination, a movable block provided with a pair of depending fingers having alined faces, a matrix supported from said block in contact with the alined faces of said fingers, a vertical plate also supported from said block, and making a right angle with said faces, and a finger for forcing said matrix into the corner between said faces and said plate.

39. In a type casting machine in combination, a reciprocable ram provided with a pair of vertical grooves, guide means attached to said ram, a movable block carried by said means provided with a pair of depending fingers adapted to occupy said grooves, a matrix supported from said block

in contact with said fingers, and means for moving said block toward and away from the face of said ram.

40. In a type casting machine in combination, a reciprocable ram, guide means attached to said ram, a block carried by said means, a matrix supported from said block, means for moving said block toward and away from said ram, and a stop for limiting the movement of said block toward said ram.

41. In a type casting machine in combination, a reciprocable ram, provided with a pair of grooves and having guide means attached thereto, a movable block mounted on said means provided with a pair of depending fingers adapted to occupy said grooves, a matrix carried by said block in contact with said fingers, a fixed mold block mounted beneath said ram, provided with two mold slots and having two pairs of grooves, each pair of grooves embracing one of said slots, and means for moving said block toward and away from said ram and mold block, the grooves in said ram registering alternately with each pair of grooves in said mold block.

42. In a type casting machine in combination, a mold block provided with two molds, a movable member operating in substantial contact with the face of said molds and adapted to close the molds during the type casting operation, said member carrying a matrix to coöperate with said molds, means for giving said member a reversing motion, means for casting type in said molds, means for pushing type from said molds into the slots in said member, and means for discharging the type from said slots.

43. In a type casting machine in combination, a reciprocable ram having two slots, a pair of plates slidably mounted in said slots, a pivoted arm mounted on said ram for transmitting motion from one of said plates to the other, a mold block mounted beneath said ram also provided with a pair of slots, a second pair of plates slidably mounted in the slots of said block, the movement of said ram first bringing one of said first mentioned slots into register with one of said second mentioned slots and then the other of said second mentioned slots, and means for operating each of said second pair of plates when its slot is in register with one of the slots in the ram.

44. In a type casting machine in combination, a mold block provided with a pair of slots, a pair of type ways one on each side of said pair of slots, a reciprocable ram having a pair of slots mounted above said block, means for casting a type in first one and then the other of the slots in said block, means for pushing type from the slots in said mold into the slots in said ram,

and means for moving the slots in said ram into register with said type ways to deposit type therein.

45. In a type casting machine in combination, a pair of type ways, a mold block having a pair of slots mounted intermediate said type ways, means for casting a type from the same matrix in first one and then the other of said slots, and means for transporting type from said slots to said type ways.

46. In a type casting machine in combination, a pair of type ways, a mold block having a pair of slots mounted intermediate 15 of said type ways, means for casting type from a single matrix in said slots, and means for transferring type from said slots to said type ways.

47. In a type casting machine in combination, a pair of type-ways, a mold block having slots intermediate said type ways, said slots dividing the distance between said type ways into three equal parts, a reciprocable ram whose stroke is equal to the distance between said slots and which is provided with slots spaced apart a distance equal to two-thirds the distance between said type-ways, means for casting type in first one and then another of said mold 25 slots, means for positioning said ram so that its slots shall lie in register first with one mold slot and type way, and then with the other mold slot and type way, means for pushing type from said mold slots into said ram slots, and means for pushing type from said ram slots into said type ways.

48. In a type casting machine in combination, a pair of type-ways, a mold block having slots intermediate said type ways, said slots dividing the distance between said type ways into three equal parts, a reciprocable ram whose stroke is equal to the distance between said slots and which is provided with slots spaced apart a distance equal to two-thirds the distance between said type ways, means for casting type in first one and then another of said mold slots, means for positioning said ram so that its slots shall lie in register first with one mold slot and type way, and then with the other mold slot and type way, means for pushing type from said mold slots into said ram slots, and simultaneously 45 operated means for pushing type from said ram slots into said type ways.

49. In a type casting machine, the combination with the matrix and mold of a pump cylinder, a valve chamber connected to said cylinder provided with an outlet extending to the mold, a valve controlling said outlet having a stem, and a spring pressed head connected to said valve stem.

50. In a type casting machine, the combination with the matrix and mold of a pump cylinder, a valve chamber connected to said

cylinder provided with an outlet extending to the mold, a valve controlling said outlet having a stem, a spring pressed head connected to said valve stem, and means for operating said head to open said valve.

51. In a type casting machine, the combination with the matrix and two molds, of a pump cylinder, a valve chamber connected to said cylinder provided with two outlets extending to said molds, a valve controlling each of said outlets, each valve having a stem, a spring pressed head connected to each of said valve stems, and means for operating said heads to open said valves.

52. In a type casting machine, the combination of a matrix, two molds, a metal pump having a cylinder, a valve chamber connected with said cylinder and provided with two outlets extending to said molds, a valve for each of said outlets, a ram, and means carried by said ram for operating said valves alternately.

53. In a type casting machine in combination, a matrix, two molds, a metal pump having a cylinder, a valve chamber connected with said cylinder and provided with two outlets extending to said molds, a valve for each of said outlets, a ram, and a movable bolt carried by said ram for operating said valves alternately, and means for moving said bolt.

54. In a type casting machine in combination, two molds, a metal pump having a cylinder, a valve chamber connected with said cylinder and provided with two outlets extending to said molds, a valve for each of said outlets, a ram, a movable bolt carried by said ram for operating said valves alternately, a matrix box also carried by said ram contacting with said bolt, and means for moving said matrix box to operate said bolt.

55. In a type casting machine in combination, a mold, a metal pump, a valve chamber connected to said pump having an outlet extending to the mold, a valve for said outlet, a reciprocating ram, a matrix box carried by said ram having a sliding connection therewith, means for moving said matrix box transversely of the line of movement of said ram, and means for operating said valve by the movement of said matrix box.

56. In a type casting machine in combination, a mold, a metal pump, a valve chamber connected to said pump having an outlet extending to the mold, a valve for said outlet, a reciprocating ram, a matrix box carried by said ram having a sliding connection therewith, means for moving said matrix box transversely of the line of movement of said ram, and means for operating said valve simultaneously with said matrix box.

57. In a type casting machine in combina- 130

tion, a matrix, two molds, a metal pump having a valve chamber provided with two outlets extending to said molds, valves for said outlets, contact heads for operating said valves, a reciprocable ram, means for giving said ram a reversing movement, means for holding said ram stationary at each end of its path of movement, a movable bolt carried by said ram adapted to engage said heads alternately, and means for forcing said bolt against one or the other of said heads when the ram is stationary.

58. In a type casting machine in combination, two molds, a metal pump having a valve chamber provided with two outlets extending to said molds, valves for said outlets, contact heads for operating said valves, a reciprocable ram, means for giving said ram a reversing movement, means for holding said ram stationary at each end of its path of movement, a movable bolt carried by said ram adapted to engage said heads alternately, a matrix box also carried by said ram adapted to contact with one end of said bolt, and means for forcing said matrix box against said bolt to operate one or the other of said heads, while the ram is stationary.

59. In a type casting machine in combination, a chocker rod, means for reciprocating said rod, a reciprocable ram, a cam for operating said ram, means operated from said rod for connecting and disconnecting said ram with said cam, and mechanism also operated from said rod for holding said ram stationary while it is disconnected from said ram.

60. In a type casting machine in combination, a chocker rod, means for reciprocating said rod, a reciprocable ram, a cam for operating said ram, means operated from said rod for connecting and disconnecting said ram with said cam, mechanism also operated from said rod for holding said ram stationary while it is disconnected from said ram, a movable matrix, and means for moving said matrix operated from said rod.

61. In a type casting machine in combination, a chocker rod, means for reciprocating said rod, a reciprocable ram, a cam for operating said ram, means operated from said rod for connecting and disconnecting said ram with said cam, mechanism also operated from said rod for holding said ram stationary while it is disconnected from said ram, a matrix box mounted on said ram, and means for moving said box relatively to said ram, said means being operated from said rod.

62. In a type casting machine, a reciprocable ram, guide means attached to said ram, a matrix box mounted on said means, a rock shaft, an arm splined to said shaft for operating said matrix box, means for rocking said shaft and means for reciprocating said ram.

In witness whereof, I hereunto subscribe my name this 21st day of November, A. D., 1912.

OTTO G. SCHMITT.
